US0D1105410S

(12) **United States Design Patent** (10) **Patent No.:** **US D1,105,410 S**
(45) **Date of Patent:** **** Dec. 9, 2025**

(54) **DUST COVER**

(71) Applicant: **Shenzhen TPH Technology Co., Ltd.**,
Shenzhen (CN)

(72) Inventor: **Xuan Zeng**, Shenzhen (CN)

(73) Assignee: **Shenzhen TPH Technology Co., Ltd.**,
Shenzhen (CN)

(**) Term: **15 Years**

(21) Appl. No.: **29/969,795**

(22) Filed: **Oct. 24, 2024**

(51) LOC (15) Cl. **24-02**

(52) U.S. Cl.

USPC **D24/109**

(58) **Field of Classification Search**
